ATTORNEY.

UNITED STATES PATENT OFFICE.

HERMANN KROPFF, OF NEW YORK, N. Y.

AIR-COOLING APPARATUS.

SPECIFICATION forming part of Letters Patent No. 271,716, dated February 6, 1883.

Application filed April 24, 1882. (No model.)

To all whom it may concern:

Be it known that I, HERMANN KROPFF, of the city, county, and State of New York, have invented certain new and useful Improvements 5 in Air-Cooling Apparatus, of which the following is a specification.

This invention relates to an improved apparatus for cooling air in large quantities in a very effective manner by a combination of 10 surface-cooling and spray-cooling; and the invention consists of a combination of devices, as set forth in the claims.

The refrigerating-liquid is admitted by a pipe to the lower part of the space surrounding the 15 air-channels, rises therein to a level with the upper edge of the same, and is shed in a thin sheet over the inner surface of the air-channels and dropped in the form of a spray through the lower chamber to the bottom of the same, 20 from which it is conducted off by a discharge-pipe. The upper ends of the air-channels are provided with spiral deflectors, whereby a spiral course is imparted to the air in its passage through the air-channels.

25 The accompanying drawing represents a vertical central section of my improved air-cooling apparatus.

A represents an exterior casing of suitable dimensions, and of cylindrical, oblong, or other 30 shape, which is closed at the top and bottom. The casing A is provided at the upper part with an air-induction pipe, a, and at the lower part, at a point diagonally opposite to the air-induction pipe, with an air-eduction pipe, a'. The middle portion of the casing A between 35 the induction and eduction pipes a a' is arranged with a series of vertical air pipes or channels, B, which are supported at the upper and lower ends by perforated diaphragms B'. To the space formed around the series of air-pipes B is admitted, by a supply-pipe, b, at a point near the lower diaphragm B', the refrigerating-liquid, which rises then vertically in 40 the space surrounding the air-pipes, its motion being in opposite direction to that of the air-currents passing through the air-pipes B. When the refrigerating-liquid arrives at a level with the upper ends of the air-pipes it 45 passes through perforations in the upper diaphragm B' into the air-pipes B, and is shed in a thin sheet over the inner surface of the same

to the lower edge of the pipes, from whence it drops in a finely-divided spray to the bottom, to be conducted off by the discharge-pipe d. The circulation of the air through the apparatus is kept up by a suitable air-forcing apparatus, the air entering first to the distributing-chamber C, passing then down through the air-pipes B and through the spray of refrigerating-liquid in the drip-chamber D to the pipe, 60 conducting the air to the place of use.

The circulation of the refrigerating-liquid is kept up by means of a pump, whereby the refrigerating-liquid—such as ice-water, brine, &c.—is returned to the air-cooler after being 65 cooled to a low temperature by means of ice or a refrigerating apparatus. The air which passes through the pipes is first brought into direct surface contact with the cooling-liquid, whereby its temperature is considerably reduced, and is finally forced, on arriving at the lower end of the air-pipes, through the drippings or sprays of the refrigerating-liquid in the drip-chamber, whereby the temperature is 70 still further lowered by the direct action of the liquid, and thereby the air at the same time washed and purified. The air is thus chilled 75 both by surface contact and by the direct passage through the fine sprays of the refrigerating-liquid, to be thence conducted off for further use. To impart to the air forced through the air-pipes B a spiral course, short spiral 80 deflectors e are employed, which are inserted into the upper ends of the pipes and supported on a vertical diametrical bearing-strip of 85 slightly larger diameter than the air-pipes, as shown in the drawing. These deflectors impart to the air a spiral motion, so that it passes in a more circuitous course along the cooling-surface of the refrigerating-liquid, which assists 90 materially in rapidly lowering the temperature of the air.

The apparatus is specially designed for cooling large spaces, such as fermenting and storage vaults of breweries, packing-houses, and 95 the like. It is of simple and compact construction, and can be readily put up in any required size and at any available place.

I am aware that air has been cooled in pipes surrounded by cooling-liquid and by sprayed 100 liquid.

I am also aware that cooling-liquid has been

mingled with air in pipes or chambers and the air conducted to apartments for cooling purposes.

Having thus described my invention, I claim 5 as new and desire to secure by Letters Patent—

1. An air-cooling apparatus having spiral air-deflectors inserted into the upper ends of the air-pipes, and supported on a vertical diametrical bearing-strip of larger diameter than 10 the said air-pipes, which latter conduct air and cooling-liquid from the upper to the lower chamber, substantially as described.

2. In an air-cooling apparatus, the combination of the spiral air-deflectors *e e*, the upper chamber, *C*, the air-channels *B*, lower chamber *D*, diaphragms *B'*, and supply-pipe *b*, substantially as described. 15

In testimony that I claim the foregoing as my invention I have signed my name in presence of two subscribing witnesses.

HERMANN KROPFF.
